CLAIM

The ornamental design for a hat as shown and described.

DESCRIPTION

FIG. 1 is a perspective view of the hat having a brim covered with artificial grass;

FIG. 2 is a right side view thereof;

FIG. 3 is a left side view thereof;

FIG. 4 is a top view thereof;

FIG. 5 is a front view thereof; and,

FIG. 6 is a perspective view of an alternative embodiment. The dash-dash broken lines in FIGS. 1-6 depict portions of the hat that form no part of the claimed design.

1 Claim, 6 Drawing Sheets
